[57] CLAIM

The ornamental design for a piercing earring holder, substantially as shown and described.

DESCRIPTION

FIG. 1 is a perspective view of a piercing earring holder showing my new design;

FIG. 2 is an end elevational view looking from the left with respect to FIG. 1;

FIG. 3 is a side elevational view thereof;

FIG. 4 is a top plan view thereof;

FIG. 5 is a bottom plan view thereof; and

FIG. 6 is an end elevational view looking from the right with respect to FIG. 1.
